ELECTRICAL PREHEATER FOR
CARBURETORESRudolf Steinhart, Vienna, Austria, and Anna
Hunter, Berlin, GermanyApplication August 9, 1934, Serial No. 739,112
In Germany April 11, 1934

3 Claims. (Cl. 219—38)

It is a known thing to preheat air for the carburetors of explosion engines in order to achieve better running of the engine. The preheating is effected by the most varying means, it being for example usual to place the suction pipe for the carburetor around the exhaust pipe in order to take the preheated air from there. It is also known to heat the carburetor air by electrical means.

10 The heating spirals which effect the heating of the air in this way are fixed in the suction piping so that the air is always obliged to brush past the heating spirals, even at times when it would be more advantageous not to effect any preheating. The heating spirals themselves are constantly exposed to the strong suction air of the engine, that is, of the carburetor.

15 The present invention has as its object the overcoming of this disadvantage by making it possible for the electric preheater to be lifted at will, possibly by a Bowden cable control operated from steering column or dash, out of the area of the suction pipe. By inserting an intermediate piece in the suction pipe in the place of the electric preheating element, which corresponds in size to the gap, the carburetor suction pipe can then be closed again.

20 As the element is raised out of or lowered into the suction pipe of the carburetor the electric current is switched off and on respectively, by automatic action.

25 A device is also provided that makes it possible for the exhaust gases, in the case of a misfire, not to pass through the sensitive heating spirals but to be led before reaching the latter through a flap valve provided in the suction pipe, which valve is automatically opened by the heavy pressure of the escape, thus making possible extensive saving of wear as regards the heating spirals.

30 In the accompanying drawing the object of the invention is depicted.

Fig. 1 shows the carburetor in front elevation with the heating device raised.

Fig. 2 is a side view of the same.

Fig. 3 is a diagrammatic elevation, partly in section.

Fig. 4 shows the heating element holder, front view and Fig. 5 shows a side view in section on the line V—V of Fig. 4.

45 In the interrupted suction pipe to the carburetor is located the heating element container 3, freely moveable in a housing 1, to which container 3 is fixed below a pipe 28 of the same section as the suction pipe. This piece of piping 28 and

the preheater 3 joined can be raised and lowered by a cable control 21 operated from the steering column of the vehicle. The heating element container 3 consists of two insulating halves 27, the heating spirals 25 lying deeply embedded in these 5 halves. The ducts 24 form a connection between the two beds. The heating elements 21 are insulated by mica plates against each other and against the lid 18 of the heating element. The slots 18 provided in these plates enable the passage of the air sucked up. On the wall 22 of the heating element sits an insulating piece 14 through holes bored in which the ends 25 of the heating wires lead to connecting screws 13 and 11. The connecting screw 11 lies in a piece of 10 tubing 28 and there a ball 2 under the pressure of a spring is fitted, which ball acts as a contact for the circuit. At a corresponding depth an insulating disc 4 is located in the housing 1, in the centre of which disc is inserted a metal piece 17 15 in such a way that it does not touch the inner edge of the housing 2 but stands at a short distance from it and is insulated in respect of the heating element container 3. On lowering the preheater container the contact with the ball 2 is 20 established through the connection screws 16 and thus the heating spiral is placed under current.

25 The slots 18, which have already been mentioned, are so distributed that at every length 30 of a longitudinal slot one winding of the heating spiral is omitted. In this way loss of heat in the heating spirals is avoided, as the current of air sucked up is exposed to the heat over the whole of its extent. The pipe 5 leads behind the housing 1 to the actual carburetor. The pipe 5 has a flap valve 6 which is under the pressure of a spring 7 and serves the purpose of allowing the passage of the gases when the engine misfires.

35 The method of working of the object of the invention is the following:—

40 If the preheater is to be brought into operation the piece of piping 28 and thus the electrical heating element housing 3 is pulled down, by pulling the wire 21 from the steering column of 45 the vehicle. The heating element housing 3 is then located between the pieces of piping 5 and 28 and through the contact ball 2 the circuit is completed for the heating spirals through the contact piece 17. The current passes through 50 the contact screw 16 to the metal piece 17 and through the contact ball 2 to the contact screw 11 fitted in the piece of piping 28, to which screw 11 the end 30 of the heating wire is joined. The other end of the heating wire is connected 55

through one of the screws 13 to the motor mass. If it is required to put the electrical preheater out of action, this also is done from the steering column of the vehicle by means of the wire 21, 5 which on operation presses upwards the piece of piping 26 and thus also the heating element container 3, with the aid of the spiral spring 8. Thus the circuit is also broken by the contact ball 2. By means of the piece of piping 26 lying between 10 the pieces of piping 5 and 29, this piece 26 corresponding in length to the gap in the piping caused by the heating element container, the smooth section in the suction pipe is once again established. The flap valve pressed down by the 15 spring 7 on to the slot 8 prevents damage to the preheater when switched on, that is to its heating spirals, in the case of misfiring, as the exhaust gases are led out through the flap valve 8 which opens owing to the pressure.

20 We claim:—

1. An electrical preheater for carburetors of internal combustion engines comprising an in-

terrupted suction pipe, a movable section of piping normally filling the gap to complete the suction pipe, an electrical heater member attached to said section of piping, means for connecting said electrical heater to an electric circuit, means for moving said section of piping out of the suction pipe, the electrical preheater automatically moving to fill the gap and means for completing the electric circuit energizing the preheater.

2. In an electrical preheater for carburetors of internal combustion engines as claimed in claim 1, a cover to the heating member, heating spirals in said cover, slots in said cover, one slot being eliminated at every winding length of said heating spirals. 15

3. In an electrical preheater for carburetors of internal combustion engines as claimed in claim 1, an outwardly opening safety valve located in the section of piping for escape of misfiring exhaust gases. 20
